CLAIM

The ornamental design for an optical mouse, as shown and described.

DESCRIPTION

FIG. 1 is a perspective view of the optical mouse;
FIG. 2 is a right side view of the optical mouse thereof;
FIG. 3 is a left side view of the optical mouse thereof;
FIG. 4 is a top view of the optical mouse thereof;
FIG. 5 is a rear view of the optical mouse thereof; and,
FIG. 6 is a front view of the optical mouse thereof.

The bottom of the optical mouse is understood to be plain and unornamented. Broken, dotted lines depict environmental effects only and form no part of the claimed design.

1 Claim, 4 Drawing Sheets

FIG.1

FIG. 2

FIG. 3

FIG. 4

FIG. 5

FIG. 6
